Filed July 6, 1964, Ser. No. 80,722

Term of patent 14 years

(Cl. D50—5)

FIGURE 1 is a three-quarter view in perspective taken from the left-hand side of the combined door handles and lockset for sliding doors embodying my new design.

FIGURE 2 is a three-quarter view in perspective taken from the right-hand side of the combined door handles and lockset for sliding doors shown in FIGURE 1.

FIGURE 3 is a side elevation view of the combined door handles and lockset for sliding doors shown in FIGURES 1 and 2.

FIGURE 4 is a bottom view of the combined door handles and lockset for sliding doors shown in FIGURE 3, and a door jamb.

FIGURE 5 is a top view of the door handles and lockset for sliding doors shown in FIGURE 4.

The broken line structure indicating a fragment of a door and a key is for illustrative purposes only.

I claim:

The ornamental design for combined door handles and lockset for sliding doors, substantially as shown and described.
